CLAIM

The ornamental design for an electromotive camera lens or similar article, substantially as shown and described.

DESCRIPTION

FIG. 1 is a front elevational view of an electromotive camera lens or similar article, showing my new design;

FIG. 2 is a top plan view thereof;

FIG. 3 is a rear elevational view thereof;

FIG. 4 is a bottom plan view thereof;

FIG. 5 is a right side elevational view thereof; and

FIG. 6 is a left side elevational view thereof.

The electromotive camera lens or similar article, substantially as shown, has a battery box at the bottom thereof and a push button at the top thereof.

FIG. 1

FIG. 2

FIG. 3

FIG. 4

FIG. 5

FIG. 6
